CLAIM

The ornamental design for a perforated card, as shown and described.

DESCRIPTION

FIG. 1 is a perspective view of a perforated card showing our new design;

FIG. 2 is a front view thereof;

FIG. 3 is a rear view thereof;

FIG. 4 is a lengthwise side view thereof; and,

FIG. 5 is a widthwise side view of thereof.

The broken line showing of portions of the perforated card is included for the purpose of illustrating environmental structure and forms no part of the claimed design.
